Inventor,
Hermann T. Padelt.
By *Hermann T. Padelt* atty.

UNITED STATES PATENT OFFICE.

HERMANN TRAUGOTT PADELT, OF LEIPZIG-SCHLEUSSIG, GERMANY.

CHANNEL OVEN FOR CERAMIC AND CHEMICAL PURPOSES.

Application filed June 27, 1925. Serial No. 40,012.

To all whom it may concern:

Be it known that I, HERMANN TRAUGOTT PADELT, a subject of the German Empire, and a resident of Leipzig-Schleussig, Rochlitzstrasse 22, Germany, have invented certain new and useful Improvements in Channel Ovens for Ceramic and Chemical Purposes; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to a channel oven for ceramic and chemical purposes in which the combustion air and the gas prior to entering into the baking chamber, are mixed in spaces in the oven wall, the gas and air mixture being admitted into the baking chamber not only at one point, but at several points situated at different heights.

The invention is characterized in that a greater number of mixing spaces for the gas and air mixture, said spaces comprising gas burners, are arranged above one another and the one at the side of the other in the oven wall, the gas burners being combined in several groups which are operated singly or several at the same time. Each burner group has one gas channel adapted to be regulated, while for the admission of the combustion air to the mixing spaces channels are provided which feed the air to the burner groups series-wise.

In the form of construction, illustrated in the accompanying drawings, every three mixing spaces in the oven wall are arranged to form four burner groups, every two groups being superposed and each group being supplied with gas from the generator by a gas channel arranged laterally of the burner groups. Owing to this arrangement the gas supply may be increased or reduced at will in accordance with the temperature to be obtained, or for increasing the efficiency of the oven or to supply to the baking chambers for the several burner groups more or less heat at the upper or lower portion of the same.

The arrangement is shown, by way of ex-

ample, in the accompanying drawings in which:

Fig. 1 is a longitudinal section through the oven.

Fig. 2 is a horizontal section on line A—B of Fig. 1.

Fig. 3 is a cross section through the oven, at the left half on line C—D and at the right half on line E—F of Fig. 1.

The material to be baked is transported on the platform of the carriage 1 running on rails 2. The carriage advances in the direction of the arrow 3. The left side part of the channel oven, Fig. 1, serves as baking zone, the right side part as cooling zone. The two gas supply channels 12, which come from a generator not shown in the drawing, ascend laterally of the burner groups I to IV and have horizontal branches 4, 4 extending underneath the mixing spaces 8. The gas supply is regulated by flaps 10. The burner groups I and II are supplied with gas from the left channel 12 and the burner groups III and IV from the right channel 12.

Pipes 6 in the cooling zone serve for supplying combustion air to the mixing spaces 8 with the aid of the channels 7 arranged in the masonry. These channels 7 are situated above the mixing spaces 8 with which they communicate by a port and they are adapted to be shut off by registers 9. One air supply channel 7 is provided for each row or group of burners. Peepholes 11 are arranged for the observation of the mixing spaces 8.

Claims:

1. A channel oven for burning ceramic and chemical devices having a plurality of mixing chambers formed within the walls of the oven and terminating in burners for air and gas mixture, supply channels for air, and separate supply channels for gas communicating with the mixing chambers, and separate regulating means for the air and for the gas at each mixing chamber.

2. Channel oven for ceramic and chemical purposes, comprising several mixing spaces, arranged above and at the side of one another and having air burners for the gas and air mixture, and supply channels for gas and air opening into said mixing spaces and adapted to be regulated, said

supply channels having regulating elements at the points where they communicate with said mixing spaces, said gas burners being arranged to form several burner groups.

5 3. Channel oven for ceramic and chemical purposes in which the several gas burners adapted to be regulated are arranged in rows at the side of one another and the one

above the other and in which the supply channels for supplying gas and air to the horizontal burner rows extend horizontally, each single gas channel supplying one group of burners juxtaposed in a horizontal plane.

In testimony that I claim the foregoing as my invention, I have signed my name.

HERMANN TRAUGOTT PADELT.
